UNITED STATES PATENT OFFICE.

RUDOLPH LORANG, OF CHICAGO, ILLINOIS.

DOOR-OPERATING MEANS.

1,085,619.

Specification of Letters Patent.

Patented Feb. 3, 1914.

Application filed February 1, 1913. Serial No. 745,620.

To all whom it may concern:

Be it known that I, RUDOLPH LORANG, a citizen of the United States, residing at Chicago, in the county of Cook and State of Illinois, have invented certain new and useful Improvements in Door-Operating Means, of which the following is a specification.

My invention relates to improvements in door operating means and has especial reference to means for operating sliding doors.

One of the objects of my invention is to provide means for simultaneously operating two cooperating sliding doors to open and close them.

Another object of my invention is to provide, in said operating means, an initially operable lever or handle, which shall require a minimum extent of movement to move the doors a relatively large distance and at a relatively high velocity.

Other and further objects of my invention will become readily apparent to persons skilled in the art from a consideration of the following description when taken in conjunction with the drawing, wherein,

Figure 1 is a front elevation of a piano to which my door-operating mechanism is shown applied, in the illustration; Fig. 2 is an enlarged rear view of the upper panel of the piano casing; Fig. 3 is a plan view of the panel.

In all the views the same reference characters indicate similar parts.

The piano case 10 is provided with a pair of sliding doors 11 and 12 which control access to a chamber containing a music roll of a self-playing piano. The chamber is contained back of the upper panel 13 and access may be had thereto through the opening or aperture 14 which is closable by the doors 11 and 12. The sliding doors are guided on the panel-board by cleats 15 and 16 in the usual manner.

When the piano is to be played, it is desirable that the doors 11 and 12 should be quickly and easily opened for access to the mechanism contained within the chamber closed by the doors. To this end I provide the handle 17 which is shown at the right hand side of the aperture in the front upper panel and the connecting mechanism within the chamber requires the handle 17 to be moved less than 60 degrees in order to fully

open the doors or to close them. In Fig. 2 both positions of the handle are shown in dotted lines. The handle is connected to a stud 18 which passes through the front panel-board 13 which in turn is connected to a lever arm 19. The arm 19 is guided in its movement by the guide strap 20 and at its free end is connected to a link 21 which in turn is pivotally connected to the door 12 by a cleat 22 and also to a rod 23. The rod 23 is adapted to be axially moved in the groove 24 which is located within the guiding strip or cleat 16. The right hand end of the rod 23 is connected to a link 25 and this link is connected to a centrally pivoted arm 26 the other end of which is connected to a link 27 which in turn is pivotally connected to a cleat 28 secured to the door 11.

When the doors 11 and 12 are closed, the operating parts, represented in full lines in Fig. 2, are in the positions shown, at which time the operating handle 17 is in substantially vertical position. To open the doors 11 and 12, it is only necessary to move the handle 17 to the right a distance equal to about 50 degrees when the doors 11 and 12 will be opened to their full extent, shown by vertical dotted lines in Fig. 2, and thus expose the entire aperture that is made in the panel 13. When the doors are opened the operating parts occupy the positions shown in dotted lines in Fig. 2. To close the doors 11 and 12, it is only necessary to move the handle 17 back to its vertical position.

By this mechanism the doors 11 and 12 are quickly opened by a minimum movement of the operating handle 17 and a minimum resistance is imposed by the moving mechanism to the operator's efforts in manipulating the doors, due to the particular correlation of the interengaging links, levers, and rod which moves in the groove parallel to the aperture which is closed by the doors.

Having shown and described my invention what I claim is:

In a device for operating two doors sliding oppositely on a door supporting frame, the combination of an oscillating lever, pivoted to said frame adjacent one of the doors; a link, connecting the free end of the lever with the adjacent door; a similar lever and link arrangement, for the opposite door, the lever for the latter door being pivoted intermediate its ends; a third link, pivoted to the

last mentioned lever at the end not connected with the door link, and a rod slide-
able in a groove in the frame on a line parallel with the movement of the doors and con-
necting the first mentioned door with the
5 third link at the end not connected to the lever.

In testimony whereof I hereunto set my hand in the presence of two witnesses.

RUDOLPH LORANG.

In the presence of—
W. LINN ALLEN,
MARY F. ALLEN.
